VACUUM CIRCUIT BREAKER

Hans Vatter, Berlin-Charlottenburg, Germany,
assignor to Siemens & Halske Aktiengesellschaft, Siemensstadt, near Berlin, Germany, a
corporation of Germany

Application September 14, 1936, Serial No. 100,632
In Germany September 3, 1935

4 Claims. (Cl. 200—144)

My invention relates to improvements in vacuum circuit breakers.

It is well known in the art to design vacuum circuit breakers in such a manner that the actuation of the switching members is effected inside the vacuum vessel by means of an elastic portion of the vessel wall. For instance, in glass bulb switches a portion of the glass surface has hitherto been made elastic by designing it in the form of corrugated sheet iron. Glass bulb switches have the great disadvantage in that they are comparatively fragile so that they cannot be used for rough services, particularly for military purposes on field vehicles or the like.

According to the invention, vacuum circuit breakers of high resistivity and efficiency are designed in the way illustrated by the accompanying drawing in which

Fig. 1 shows a circuit breaker in longitudinal section, and

Fig. 2 a central transverse section through a modified form of the breaker.

The enclosure of the circuit breaker shown in Fig. 1 consists of a tube 1 of vacuum-tight ceramic material. The ends of the tube are metallized as indicated at 2 and 3. One end of the tube is closed by a metallic cap 4 which is soldered at 3 to form a vacuum-tight joint. The soldering is effected in the manner that a ring 5 consisting of soldering material is at first arranged in the cap. To prevent the soldering material from flowing inside the discharge vessel a disc 6 is so arranged as to cause the molten soldering material to flow in the joint 1. The cap 4 may at the same time serve to support one electrode 8. The electrode 8 or the counter-electrode 9 may be designed at least in part as a tube and serve as a connection for a vacuum pump during the manufacturing process. The other end of the tube 1 carries, for instance, a flange-shaped extension 10, at the periphery 11 of which is soldered or welded a metallic diaphragm 12.

The counter-electrode 9 is secured to the metallic diaphragm so that when the outer portion of the electrode 9 is moved the electrodes 8 and 9 may be brought into engagement at 13. It is understood that also any other contact mechanism which is actuated upon moving the part 9, may be arranged in the interior of the tube. In some cases it may be preferable not to give the diaphragm 12 a circular form but design it in such a manner that the movement of the part 9 in the direction of one of the axes of the diaphragm 12, as shown by the arrows in the plane

of the drawing experiences a smaller resistance than in other directions of axis.

One of the electrodes is preferably formed as a ring, in the interior of which is placed the other electrode. In this manner, the movable electrode is brought into proper engagement with the other electrode, irrespective of the direction of motion of the movable electrode. By dimensioning the outer diameter of the ring in a corresponding manner the maximum deflection of the movable electrode may at the same time be limited. Fig. 2 shows a sectional view of such a vacuum circuit breaker. The movable electrode 9 carries a ring 14 inside of which is placed the fixed electrode. The electrode 9 comes into engagement with the electrode 8 independently of the direction of motion of the electrode 9. The maximum deflection is attained when the outer edge of the ring 14 contacts with the inner wall of the tube 1.

I claim as my invention:

1. As an article of manufacture, a vacuum switch comprising a tube of ceramic material adapted to be evacuated, a fixed and a movable contact element cooperatively disposed in said tube, two metal end caps for closing the two tube ends, each cap electrically connected with one of said contact elements and serving as a support therefor, each tube end having a metal layer vacuum-tight attached to its wall with which the apertaining cap is in contact and solder for vacuum-tight connecting each cap with the contacting metal layer, a protective disc arranged between each of said caps and the interior part of said tube and extending across the tube opening inside of each cap designed to confine the solder flow to the joint between the inner cap wall and the adjacent metal layer, one of said caps having an elastic wall in which the movable contact element is mounted vacuum-tight intermediate its ends to permit the movement of said element from outside.

2. As an article of manufacture, a vacuum switch comprising a tubular container of ceramic material, a metallic coating disposed on the outside surface of each end of said container, a metal cap placed over each end of said container, two coating contact electrodes movable relative to each other, each being mounted to one of said caps respectively, a solder bond tightly connecting said coating and said cap, and a protective disk arranged in said cap so as to close the interior of said container against said solder.

3. As an article of manufacture, an evacuated ceramic tube forming the enclosure of an elec-

tric control device and having a tube opening covered by a metal cap, in combination with a metallic coating disposed on and integral with the surface portion of said tube covered by said cap, solder forming a bond between said coating and said cap, said cap and said tube being designed to form an annular interstice for the reception of a ring-shaped body consisting of said solder so as to allow producing said bond by heating said body within said cap, and a protective disk arranged in said cap and closing said opening against said solder for confining the flow of said solder.

4. As an article of manufacture, an electric device comprising a container of ceramic material having an opening covered by a metal cap, in combination with a metal coating disposed on and integral with the ceramic surface of said container, a solder bond connecting said coating and said cap, and a protective member disposed in said cap so as to close said opening against said solder in order to confine the flow of said solder to the joint between cap and coating when producing said bond.

HANS VATTER.
